UNITED STATES PATENT OFFICE

2,438,462

METERED SPRAYING DEVICE FOR
MIXED LIQUIDS

Ronald B. Smith, East Orange, N. J.

Application July 1, 1944, Serial No. 543,076

4 Claims. (Cl. 299—58)

1

This invention relates to the spraying of mixed liquids with or without a supplemental air stream, and has for its principal objects the provision of a sturdy, cheap, compact and portable apparatus for such purpose which is easy to manipulate and is capable of accurately controlling or metering the proportions of the different liquids discharged through the nozzle thereof. A further object of the invention is the provision of an apparatus wherein by a simple manipulation the proportions of the mixed liquids can be varied at will within wide limits. Other objects of the invention will hereafter appear.

Heretofore, as I am well aware, as set forth in Patent No. 2,197,730 of April 16, 1940, it has been proposed to provide pumping equipment capable of delivering mixed liquids and proportioning the same at selectively variant pre-determined rates, but such equipment was complicated to construct and manipulate besides being cumbersome and relatively expensive to manufacture. My invention, while realizing many, if not all of the advantages of such equipment, is free from those drawbacks and withal is extremely dependable in operation, readily portable and convenient to manipulate.

The invention is fully set forth in the following detailed description and drawings forming a part thereof in which latter

Figure 1 is a side elevation of a spray gun embodying one form of the invention;

Figure 2 is a longitudinal section taken on the line 2—2 of Fig. 1;

Figure 3 is a transverse section taken on the line 3—3 of Fig. 1;

Figure 4 is a longitudinal section taken on the line 4—4 of Fig. 2; and

Figure 5 is another longitudinal section taken on the line 5—5 of Fig. 2.

Referring to the drawings and the construction shown therein, the reference number 1 designates the housing of the spray gun, 2 the grip, 3 the nozzle portion of each housing, 3' the nozzle carried thereby and 4 the fluid chamber of a fluid-drive motor which serves to drive a pair of gear pumps hereinafter described. Said motor is of well known construction, the same including an eccentrically mounted, cylindrical rotor element 5, having elastically mounted opposed vanes or blades 5', that is mounted on an axle 6. The latter projects through the removable plugs a—a' that in turn seal the ends of said chamber 4. Gear elements are mounted on the reduced outer ends of said axle, the same being rigidly fixed thereon by butterfly or wing nuts 8 and 8'. A

2

compressed air hose or so-called air line 9 is connected to the hollow boss 9' on the rear end of said housing, the same being adapted to deliver air into the duct 10 which serves to distribute the same via the auxiliary ducts 11 and 12 to the said chamber 4 in which it drives the rotor and to mixing chamber of said nozzle 3'. Needle valves 13 and 14 control the amount of air admitted to the chamber 4 and the mixing chamber 10 b, respectively. Two gear pumps are respectively mounted in the forward end of the gun, the same comprising fluid chambers 15 and 15' in each of which are positioned a pair of meshing gears 16 and 16', which are rotatably mounted on the stub shafts 17 and 17', respectively. Variable gears 18 and 18' are mounted respectively on the shoudered outer ends of each of the axles 17, the same being fixed thereon by butterfly nuts 19 and 19' respectively. Slotted support arms 20 and 20' are mounted on the axle 6, the said arms being respectively interposed between the gears 17 and 17' and the adjacent faces of said end plugs a, a'. Retainer bolts 22, 22' project centrally through variable gears 23, 23' and also through the slots 25 in the arms 20, 20', the same being adapted to receive locking wing nuts 24, 24', which serve to maintain said gears 23, 23' in any adjusted position on their respective support arms. Each of the latter arms has an integral, accurate, slotted 30 adjusting leg, as designated by the numerals 25 and 25', and studs 27, 27', which project through the slots in said legs and are anchored in the opposite sides of the housing and serve to maintain said support arms in any adjusted position 35 when the wing nuts 28, 28' are applied thereto and screwed home.

Liquid hose lines 29 and 29' are also connected to hollow bosses on the butt end of the gun the same serving to supply liquid under sufficient head 40 to fill the conduits 30 and 30' and to prime the gear pump chambers 15. Needle valves 31, 31' serve to regulate the flow of liquid to the gear pump chambers and such regulation is further controlled by a by-pass conduit 32 associated with 45 each gear pump chamber which is controlled by a cock 33. Each by-pass, while controlling directly the amount of liquid flowing to each gear pump chamber, necessarily controls the amount of liquid passing from its associated gear pump 50 chamber to the communicating conduit 34 or 34' which affords communication between such gear pump chamber and the nozzle of the gun.

The invention is especially suitable for use wherever the exact metering of one or more liquids is required and is free from the annoyance

caused by stoppage of flow of the mixed liquids or a single liquid where dependance is had solely upon gravity for effecting such flow or where suction is relied upon to effect the same and air bubbles enter the system and which stoppage often results in spoilage of important work. The invention is also especially applicable for use in the spraying of mixed liquids in those cases where it is essential that the same be mixed in exact proportions at the nozzle, as for example in spraying of a silver solution and a precipitant in the production of high grade mirrors or reflectors, since once adjusted my improved spray gun steadily delivers the mixed solutions in metered amounts without the possibility of any interference of such delivery or the proportioning of the mixed liquids by air bubbles entering the system or by variations in flow where reliance is had upon gravity. Furthermore, the possibility of the nozzle becoming clogged is minimized especially since nozzles having relatively minute orifices such as used in the atomizer type of spray gun are not required in many of the applications for which the invention is adapted, though if the character of the work requires such small nozzle apertures the same may of course be employed.

Various modifications of the construction herein described may be made without departing from the spirit of the invention as embraced within the scope of the appended claims.

Having thus described the invention, what I claim is:

1. In a liquid dispensing device, the combination comprising a housing, a nozzle member associated therewith, a plurality of gear pumps for supplying liquid to said nozzle, each gear pump having an inlet conduit and an outlet conduit, a fluid-drive motor, including a rotor element, mounted in said housing, means for supplying motive fluid thereto, a train of variable gearing operatively connecting each gear pump to said rotor and means for simultaneously conducting liquid discharged under pressure by each pump to said nozzle member.

2. In a liquid dispensing device, the combina-

tion comprising a housing having a plurality of inlet conduits and a common discharge outlet, a fluid-drive motor, including a rotor element, said motor having a pair of retractible, elastically mounted blades, interposed in one of said inlet conduits, a train of at least three gears operatively connected to said rotor, the middle gear of said train being readily replaceable; and a gear pump for delivering liquid under pressure to said discharge outlet, the latter pump being also operatively connected to said train of gears.

3. In a spray gun, the combination comprising a main housing, an associated spray nozzle, means for conducting a plurality of fluids from said main housing to said spray nozzle under pressure, means for supplying a plurality of fluids to said main housing and fluid-operative metering means carried by said housing and directly controlled by one of the said latter fluids for proportioning with respect to each other the amounts of the different fluids delivered from said housing to said spray nozzle.

4. In a device for metering liquid to be mixed the sub-combination comprising a fluid-drive motor having a rotor element, a pair of auxiliary gear pumps, and means including a separate train of variable gears interconnecting the rotor of the motor with one gear of each gear pump for metering the amounts of liquid discharged by each of said gear pumps in response to the speed of rotation of the rotor.

RONALD B. SMITH.
